UNITED STATES PATENT OFFICE.

GUY B. SCOTT OF PAINESVILLE, OHIO, ASSIGNOR OF ONE-HALF TO ELMER FRESH-WATER, OF PAINESVILLE, OHIO.

TRIPPING MECHANISM FOR SCOOPS.

Application filed May 11, 1925. Serial No. 29,317.

My invention relates to tripping mechanism and particularly to mechanism of this character adapted for use with power excavators. The invention is utilized for tripping the latch controlling the discharge door of the excavator scoop. The object of the invention is to provide simple and conveniently-actuated mechanism of this character by which the door latch of the scoop may be controlled by the operator of the excavating machine, without the necessity of employing an additional man for performing this duty. More particularly, the invention relates to such mechanism in which the means controlling the trip are connected to one of the control levers for the main scoop-actuating mechanism so that such trip controlling means is a part of a unitary device including such scoop-control lever. It is intended that the trip controlling means shall be actuated by the same hand of the operator as actuates the scoop-control-lever. The trip controlling means have a selective limited movement independent of the scoop-control lever, or may be locked to the last-mentioned lever so as to move therewith. In the latter event, the movement of the scoop-control lever and the trip control has no effect upon the scoop latch controlling means.

The annexed drawings and the following description set forth in detail certain means embodying my invention, such means constituting, however, but one of the various forms in which the principle of the invention may be applied.

In said annexed drawings:

Figure 1 is a fragmentary side elevation of a conventional type of scoop excavator provided with one form of my improved tripping mechanism;

Figure 2 is a vertical longitudinal sectional view, upon an enlarged scale, of a cable winding drum and associated elements forming features of my improved tripping mechanism, the section being taken in the plane indicated by the line II-II, Figures 1 and 3;

Figure 3 is a vertical transverse sectional view, taken in the plane indicated by the line III-III, Figure 2;

Figure 4 is a vertical cross sectional view of the upper end of a scoop-control lever,

and elements associated therewith to form the type of scoop latch tripping mechanism shown in Figure 1;

Figure 4^a is a side elevation, upon an enlarged scale, of a swivel pulley and a hanger therefor depending from the excavator platform, and utilized for a purpose hereinafter fully explained;

Figure 5 is a side elevation of a second and preferred form of scoop latch tripping mechanism, the same being shown in association with one of the scoop-control levers of a standard form of power excavator;

Figure 6 is a front elevation, upon an enlarged scale, of a multiple-pulley block utilized for a purpose hereinafter fully explained;

Figure 7 is a vertical transverse section, taken in the plane indicated by the line VII-VII, Figure 6;

Figure 8 is a horizontal section, taken in the plane indicated by the line VIII-VIII, Figure 6;

Figure 9 is a fragmentary side elevation of a conventional type of scoop excavator provided with the preferred form of scoop latch tripping mechanism shown in Figure 5.

Referring particularly to the annexed drawings, in the several views of which the different elements are respectively designated by the same ordinals, I suggest a standard form of power scoop-excavating machine by 55 a platform 5, a swinging boom 6 which is supported at one end by means of a horizontal pin 65 upon a boom support 64 pivotally mounted by means of vertical king-pins (not shown) upon forwardly projecting shoulder 60 journals 63 secured to the platform 5, a scoop 7 depending from the boom 6 and adapted to be moved upon a trolley longitudinally of the boom 6 by means of power devices (well-known) actuated by standard 65 control levers mounted upon the platform 5, said scoop 7 having a discharge door controlled by a swinging latch 8. Mounted upon the platform 5 is a supporting frame 9 within the upper end of which is mounted a 100 stationary transverse shaft 10 upon which is carried a freely-rotatable cable drum 11. One end of the drum 11 is formed with a housing portion 12 within which is contained a band spring 13 connected at one end 105 14 to the inner wall of the housing 12 and

connected at the opposite end 15 to the stationary shaft 10. The housing 12 is provided with a removable cover plate 16. Journalled within the frame 9 beneath the stationary shaft 10, and in parallel relation therewith, is a rock shaft 17 upon which is secured by means of a set screw 18 a bell crank 19 having arms 22 and 23. Surrounding the housing 12 is a brake band 20 whose opposite ends are pivotally secured as at 21 to the arms 22 and 23, respectively, of the bell crank 19. Keyed to one end of the rock shaft 17 is an arm 38 to which is pivotally and adjustably secured one end of a rod 37 whose other end is secured either to a two-part disk 32, as shown in Figure 1, or to a two-part plate or clamp 42, as shown in Figure 5, said disk 32 or clamp 42 turning freely upon a pivot 25.

Referring particularly to Figures 1 and 4, I designate one of the control levers for actuating the scoop 7 by the ordinal 24. In this type of my improved mechanism, I have replaced one of the standard control levers for the scoop by the lever 24 and have organized this lever 24 so as to accommodate the control for my improved tripping mechanism and to allow for the operation of the same. The standard form of detent for the scoop-control lever has been replaced by the vertically reciprocable rod 26 normally held in its upper position by means of spring 26⁴, this rod 26 being pivotally secured to an arm 26' which is pivoted intermediate its ends upon a pin 26³ mounted in the lever 24, the other end of this arm 26' being pivotally secured to a second rod 26² adapted to engage at its lower end with a notch segment 27. It is evident that normally the rod 26² is engaged with the segment 27 and that the release of the same is necessary before the lever 24 can be actuated to move the scoop 7. Pivotally secured to the top of the lever 24 upon a pin 28 is a rocking handle 29 formed with a central chamber 29' intersected by a pin 51 upon which is pivoted intermediate its ends a link 52 to whose respective ends are secured an upwardly extending rod 30 and a downwardly extending detent member 53. The upper end of the handle 29 is closed by an externally threaded plug 66 having an upper socketed end 67 within the socket of which is mounted a spring 30' adapted normally to hold the rod 30 in its upper position. The lower end of the detent member 53 is adapted to engage notches 31 formed in the upper part of the lever 24. There are two of the notches 31 and they are spaced by a shoulder 68 of the lever 24, plainly shown in Figure 4. It is evident then that the spring pressed rod 30-52-53 normally locks the handle 29 to the lever 24. It is also evident that the depression of the rod 30 by the thumb of the operator against the pressure of the spring 30' will release the detent 53 from the notch 31, (the handle 29 being in the position shown in full lines in Figure 4) and allow for the movement of the handle 29 to the position shown in dot-and-dash lines, Figure 4. The amount of such pivotal movement of the handle 29 is limited by the construction of the notches 31 and the shoulder 68, as plainly shown in Figure 4, and the release of the pressure of the operator's thumb from the rod 30 will again cause the locking of the handle 29 and the lever 24 in the position shown in dot-and-dash lines, Figure 4, under the action of the spring 30'. The movement of the handle 29, relative to the lever 24, from the full line position shown in Figure 4 to the dot-and-dash position shown therein is designed to apply the brake band 20 to the drum 11. This result is effected in the following manner. Secured to an offset 35 formed upon the rocking handle 29 is the upper end of a rod 34 which is pivotally and adjustably secured to this offset 35 and is loosely pivotally connected at its lower end at a predetermined point 33 to the disk 32. The rod 37 is connected to the disk 32 at a point 36 remote from the point 33. It is evident that the rocking of the handle 29 with relation to the lever 24 will pull the rod 34 and thus through the train of mechanism hereinbefore described result in the rocking of the bell crank 19 and the clamping of the brake band 20. Connected at one end to the latch 8 of the scoop 7 is a cable 39 which extends rearwardly through a pulley block 60 and over a swivel pulley 59 supported upon the excavator and thence upwardly and is secured at its opposite end to the cable drum 11. Normally the brake band 20 is loose upon the cable drum 11. It will be apparent that as the scoop 7 is moved forwardly along the boom 6, the cable 39 will unwind from the drum 11, the consequent turning movement of the drum 11 winding the spring 13. When the scoop 7 is retracted along the boom 6, the unwinding of the spring 13 will turn the drum in the opposite direction effectively to wind up the cable 39. The nature of the connection between the lever 24 and the bell crank 19 is such as not materially to effect the tightening of the brake band 20 when the lever 24 is actuated. Therefore, when the rocking handle is locked to the lever 24, the actuation of the latter for effecting the movements of the scoop 7 will not affect the latch 8. When it is desired to release the latch 8 of the scoop 7, in order that the contents of the latter may be dumped, the detent 53 is released from the right hand notch 31 and the handle 29 moved from the full line position shown in Figure 4 to the dot-and-dash position shown in said figure when, upon a further

actuation of the lever 24 to cause an additional forward movement of the scoop 7, the cable 39 will be prevented from moving forwardly, due to the application of the brake band 20 to the drum 11, so that the latch 8 will be restrained and thus released when the scoop 7 moves forwardly, whereby the discharge from the scoop will be effected.

It has been mentioned that the boom support 64 is pivotally connected to the excavator frame and that in turn the boom 6 is pivotally connected in a perpendicular plane to the boom support 64, so that the cable 39 will pass through the pulley block 60 in many different directions under various positions of the boom 6. To avoid wearing the cable 39, I provide the pulley block 60 furnished with a plurality of pulleys arranged in intersecting planes thus to furnish a rolling surface for the movement of the cable 39 in various directions. Particularly I provide two pairs of pulleys 61 and 62 respectively, mounted upon journal pins 63. One of these pairs 61 is arranged in parallel relation in a horizontal plane and the other pair 62 arranged in parallel relation in a vertical plane. It is evident that whatever the direction of travel of the cable 39, a rolling surface will be provided for its travel through the pulley block 60. In order to direct the cable 39 into the pulley block 60, I provide an additional swivel pulley 59 which in detail comprises a U-shaped hanger 57 dependently supported from the platform 5 intermediate the drum 11 and the pulley block 60, to the cross arm of which hanger 57 is secured a clevis 58 which passes through the eye of a small pulley block carrying a pulley 59 under which passes the cable 39, all as plainly shown in Figures 1 and 4.

When it is desired to release the drum 11 from the brake band 20, the handle 29 is moved from the position shown in dot-and-dash line, Figure 4, to the full line position shown therein. In order that the brake band 20 may be positively pulled up from the drum 11, I secure to the outer upper surface of the band 20 one end of a spring 49 whose other end is secured to the angular end 48 of a vertical bar 47 secured at its lower end to the supporting frame 9.

In the preferred type of tripping mechanism shown in Figures 5 and 9, I utilize the standard scoop-control lever 41 forming a part of the standard excavating mechanism. In order to accommodate my tripping mechanism, I reorganize this lever 41 only in the following particulars. I replace the pin upon which the detent 26 is ordinarily pivoted by a longer pin 54 and I drill the lever 41 to take a stop pin 70 whose purpose will be hereinafter fully explained. As is well known, one type of standard scoop-control lever 41 is provided with a spring controlled arm 43 connected at its lower end to one end

of a centrally pivoted link 55 whose other end is connected to the upper end of the detent 26 adapted to engage at its lower end with the notched segment 27.

Mounted upon the pivot 25 is a two-part clamp 42 to which is connected at the point 33 the rod 34 whose upper end is secured to the angular extension 46' of a trip lever 46 which is pivoted between the portions 46 and 46' upon the pin 54. A spring 56 connected to the member 46' at one end and to the pivot 25 at the other end tends to hold the finger trip 46 normally in the position shown in Figure 5. This is an outer position of the finger trip 46 and the extreme position is determined and limited by the pin 70. It is evident that a finger or two of the same hand of the operator that is used for actuating the lever 41 will serve to pull the finger trip 46 in toward the handle portion 50 of the lever 41 so as to apply the brake band 20. The finger trip 46 will be held in this inner position until the scoop 7 is moved forwardly to release the latch 8 and then the release of the trip 46 will permit the return of the same to its normal outer position shown in Figure 5.

What I claim is:

1. Tripping mechanism for excavator scoops comprising, in combination with the excavator and scoop and operating means therefor including an actuating lever, a scoop-door retaining latch, a cable drum mounted upon the excavator, a cable connection between said latch and said drum, braking means for preventing the rotation of said drum, means tending positively to rotate said drum to wind up said cable, and means unitary with said lever for controlling the operation of said braking means. 100

2. Tripping mechanism for excavator scoops comprising, in combination with the excavator and scoop and operating means therefor including an actuating lever, a scoop-door retaining latch, a cable drum mounted upon the excavator, a cable connection between said latch and said drum, braking means for preventing the rotation of said drum, a coiled spring connected to said drum and drum shaft tending positively to rotate said drum to wind up said cable, and means unitary with said lever for controlling the operation of said braking means. 110

3. Tripping mechanism for excavator scoops comprising, in combination with the excavator and scoop and operating means therefor including an actuating lever, a scoop-door retaining latch, a cable drum mounted upon the excavator, a cable connection between said latch and said drum, a brake band surrounding said cable drum, means tending positively to rotate said drum to wind up said cable, means unitary with said lever for actuating said brake band, and means permitting said brake-band-actuating 125

means to have a selective movement independently of said lever, the movements of the lever not affecting the brake band.

4. Tripping mechanism for excavator scoops comprising, in combination with the excavator and scoop and operating means therefor including an actuating lever, a scoop-door retaining latch, a cable drum mounted upon the excavator, a cable connection between said latch and said drum, a brake band surrounding said drum, a coiled spring connected to said drum and drum shaft tending positively to rotate said drum to wind up said cable, means unitary with 10 said lever for actuating said brake band, and means permitting said brake band actuating means to have a selective movement independent of said lever, the movements of the lever not affecting the brake band.
5. Tripping mechanism for excavator scoops comprising, in combination with the excavator and scoop and operating means therefor including an actuating lever, a scoop-door retaining latch, a cable drum 25 mounted upon the excavator, a cable connection between said latch and said drum, a brake band surrounding said drum, means tending positively to rotate said drum to wind up said cable, and a finger grip member mounted upon said actuating lever and 30 connected to said brake band, said grip member being operable by the same hand that actuates the lever and having a limited selective movement independent of the lever, the 35 movements of the lever not affecting the brake band.

6. Tripping mechanism for excavator scoops comprising, in combination with the excavator and scoop and operating means 40 therefor including an actuating lever, a scoop-door retaining latch, a cable drum mounted upon the excavator, a cable connection between said latch and said drum, a brake band surrounding said drum, means 45 tending positively to rotate said drum to wind up said cable, a finger grip member pivotally mounted upon said actuating lever and connected to said brake band, said grip member being operable by the same hand 50 that actuates the lever, the movements of the lever not affecting the brake band.

7. Tripping mechanism for excavator scoops comprising, in combination with the excavator and scoop and operating means 55 therefor including an actuating lever, a scoop-door retaining latch, a cable drum mounted upon the excavator, a cable connection between said latch and said drum, a brake band surrounding said drum, means 60 tending positively to rotate said drum to wind up said cable, a finger grip member pivotally mounted upon and adjacent the top of said actuating lever and connected to said brake band, the movements of the lever 65 not affecting the brake band.

8. Tripping mechanism for excavator scoops comprising, in combination with the excavator and scoop and operating means therefor including an actuating lever, a scoop-door retaining latch, a cable drum 70 mounted upon the excavator, a cable connection between said latch and said drum, braking means for preventing the rotation of said drum, means tending positively to rotate said drum to wind up said cable, a rock shaft 75 mounted in the excavator frame, a bell crank secured to said shaft and having its two arms secured respectively to the ends of said brake band, a finger grip member pivotally mounted upon and adjacent the top of said 80 actuating lever, and operating connections between said grip member and said rock shaft, the movements of the lever not affecting the braking means.

9. Tripping mechanism for excavator 85 scoops comprising, in combination with the excavator and scoop and operating means therefor including an actuating lever, a scoop-door retaining latch, a cable drum 90 mounted upon the excavator, a cable connection between said latch and said drum, braking means for preventing the rotation of said drum, means tending positively to rotate said drum to wind up said cable, a rock shaft mounted in the excavator frame, a bell 95 crank secured to said shaft and having its two arms secured respectively to the ends of said brake band, a finger grip member pivotally mounted upon and adjacent the top of said actuating lever, operating connections 100 between said grip member and said rock shaft, the pivotal movement of said grip member toward said lever tending to tighten said braking means, and means for limiting the pivotal movement of said grip member 105 away from said lever, the movements of the latter not affecting the braking means.

10. Tripping mechanism for excavator scoops comprising, in combination with the excavator and scoop and operating means 110 therefor including an actuating lever, a scoop-door retaining latch, a cable drum mounted upon the excavator, a cable connection between said latch and said drum, a brake band surrounding said cable drum, 115 means tending positively to lift said band from said drum, means tending positively to rotate said drum to wind up said cable, means unitary with said lever for actuating said brake band, and means permitting said 120 brake band actuating means to have a selective movement independently of said lever, the movements of the lever not affecting the brake band.

11. Tripping mechanism for excavator 125 scoops comprising, in combination with the excavator, a boom support connected thereto by a vertical pivot pin, a boom connected to said support by a horizontal pivot pin, a scoop supported by said boom, and operating 130

means for said scoop including an actuating lever mounted upon said excavator, a scoop-door retaining latch, a cable drum mounted upon the excavator, a pulley block secured to said boom support and having a plurality of pulleys arranged in intersecting planes, a cable connection between said latch and said drum, said cable connection passing through said pulley block so as to play over the several pulleys, a brake band surrounding said cable drum, means tending positively to rotate said drum to wind up said cable, and means for actuating said brake band, said latter means having a selective movement independent of said lever, the movements of the lever not affecting the brake band.

12. Tripping mechanism for excavator scoops comprising, in combination with the excavator, a boom support connected thereto by a vertical pivot pin, a boom connected to said support by a horizontal pivot pin, a scoop supported by said boom, and operating means for said scoop including an actuating lever mounted upon said excavator, a scoop-door retaining latch, a cable drum mounted upon the excavator, a pulley block secured to said boom support and having a plurality of pulleys arranged in intersecting planes, a cable connection between said latch and said drum, said cable connection passing through said pulley block so as to play over the several pulleys, a brake band surrounding said cable drum, means tending positively to rotate said drum to wind up said cable, means unitary with said lever for actuating said brake band, and means permitting said brake band actuating means to have a selective movement independently of said lever, the movements of the lever not affecting the brake band.

13. Tripping mechanism for excavator scoops comprising, in combination with the excavator, a boom support connected thereto by a vertical pivot pin, a boom connected to said support by a horizontal pivot pin, a scoop supported by said boom, and operating means for said scoop including an actuating lever mounted upon said excavator, a scoop-door retaining latch, a cable drum mounted upon the excavator, a pulley block secured to said boom support and having two pairs of respectively parallel pulleys whose axes lie in respectively perpendicular planes, a cable connection between said latch and said drum, said cable connection passing through said pulley block so as to play over the several pulleys, a brake band surrounding said cable drum, means tending positively to rotate said drum to wind up said cable, means unitary with said lever for actuating said brake band, and means permitting said brake band actuating means to have a selective movement independently of said lever, the movements of the lever not affecting the brake band.

14. Tripping mechanism for excavator scoops comprising, in combination with the excavator, a boom support connected thereto by a vertical pivot pin, a boom connected to said support by a horizontal pivot pin, a scoop supported by said boom, and operating means for said scoop including an actuating lever mounted upon said excavator, a scoop-door retaining latch, a cable drum mounted upon the excavator, a pulley block secured to said boom support and having two pairs of respectively parallel pulleys whose axes lie in respectively perpendicular planes, a swivel pulley support and

80 pulley therein mounted upon the excavator intermediate said cable drum and said pulley block, a cable connection between said latch and said drum, said cable connection passing through said pulley block so as to play over the several pulleys and also passing over said swivel pulley, a brake band surrounding said cable drum, means tending positively to rotate said drum to wind up said cable, and means for actuating said 90 brake band, the latter means having a selective movement independent of said lever, the movements of the lever not affecting the brake band.

15. Tripping mechanism for excavator scoops comprising, in combination with the excavator, a boom support connected thereto by a vertical pivot pin, a boom connected to said support by a horizontal pivot pin, a scoop supported by said boom, and operating means for said scoop including an actuating lever mounted upon said excavator, a scoop-door retaining latch, a cable drum mounted upon the excavator, a pulley block secured to said boom support and having two pairs of respectively parallel pulleys whose axes lie in respectively perpendicular planes, a swivel pulley-support and pulley therein mounted upon the excavator intermediate said cable drum and said pulley block, a cable connection between said latch and said drum, said cable connection passing through said pulley block so as to play over the several pulleys and also passing over said swivel pulley, a brake band surrounding said cable drum, means tending positively to rotate said drum to wind up said cable, means unitary with said lever for actuating said brake band, and means permitting said brake band actuating means to have a selective 120 movement independently of said lever, the movements of the lever not affecting the brake band.

16. Tripping mechanism for excavator scoops comprising, in combination with the excavator and scoop and operating means therefor including an actuating lever, a scoop-door retaining latch, a cable drum

6
mounted upon the excavator, a cable connection between said latch and said drum, braking means for preventing the rotation of said drum, means tending positively to rotate said drum to wind up said cable, a rock shaft mounted in the excavator frame, a bell crank secured to said shaft and having its two arms secured respectively to the ends of said brake band, a finger grip member pivotally mounted upon and adjacent the top of said actuating lever, operating connections between said grip member and said rock

shaft, the pivotal movement of said grip member towards said lever tending to tighten said braking means, means tending positively to free said braking means from said drum, means tending positively to move said grip member away from said lever, and means for limiting the pivotal movement of said grip member away from said lever, the movements of the latter not affecting the braking means. ¹⁵

Signed by me this 23rd day of April, 1925.
GUY B. SCOTT. ²⁰
